UNITED STATES PATENT OFFICE.

BENTLEY A. PLIMPTON, OF VICTOR, NEW YORK.

SUPPORT FOR ELECTRIC CONDUCTORS.

1,362,038.

Specification of Letters Patent. Patented Dec. 14, 1920.

Application filed April 10, 1920. Serial No. 372,811.

To all whom it may concern:

Be it known that I, BENTLEY A. PLIMPTON, a citizen of the United States of America, residing at Victor, in the county of Ontario and State of New York, have invented certain new and useful Improvements in Supports for Electric Conductors, of which the following is a specification.

My invention relates to supports for electric conductors, more particularly of the type adapted for use with electrical systems employing three conductors spaced at equidistant points from a central field.

An important purpose of the invention is to provide a construction requiring a minimum quantity of metal, and correspondingly economical to manufacture.

An equally important object of my improvement is to construct and arrange the parts in such a way as to afford maximum rigidity and strength, so as to successfully resist all possible strains.

A further purpose of the invention is to construct a conductor support that can be readily attached to a pole without any fitting, and which can be used with poles of minimum height.

Other advantages of the invention will be made clear from the following detailed description, in conjunction with the accompanying drawings, the novel features being pointed out in the claims at the end of the specification.

In the drawings:

Figure 1 is a side elevation, showing the application of a preferred embodiment of the invention to a pole;

Fig. 2 is a front elevation of the same, and

Fig. 3 is a plan view.

The fundamental purposes and features of the invention may be practically applied in various types of construction, and while the present embodiment is intended to illustrate my ideas, it does not limit the application of the invention to the precise structure disclosed.

A designates a pole to which is attached a cross arm B. The latter may be of angle iron or wood construction, and is secured to the pole by a bolt b or other convenient means, and is intended to carry an insulator at each end.

C designates a vertical arm, preferably formed of angle iron, and attached to the pole by means of bolts c. In the construc-

tion shown, the vertical arm C is positioned on the opposite side of the pole from the cross arm B, and is rigidly connected to the cross arm by bracing members D. The 60 bracing members D are formed integral with the vertical arm C and have their lower ends attached to the cross arm by bolts d or other suitable means.

The bracing members D are preferably 65 formed by centrally splitting the lower end of the vertical arm C, thus providing a bifurcated portion and affording diverging bracing strips which straddle the pole, as shown in Fig. 1, in order to bring the lower 70 ends of the bracing strips D to the opposite side of the pole for attachment to the cross arm B.

In order to afford a support for the upper insulator, the vertical arm C is bent horizontally at its upper end, affording the portion E which extends at right angles to the cross arm B, or in the same direction as the conductors, and it is to be understood that a suitable insulator is mounted upon the 80 horizontal portion E.

It is not essential that the vertical arm C and the cross arm B be on opposite sides of the pole, but this arrangement affords an extremely simple method of holding the 85 cross arm with great rigidity, since the bracing members D are sufficiently stiff to prevent any torsional or other strains from materially affecting the cross arm.

The structure is exceedingly easy to apply, and if there is a slight discrepancy between the position of the cross arm B and the vertical arm C, the bracing strips D can be bent slightly to accommodate their attachment to the cross arm. The structure 95 entirely eliminates the necessity of fitting any parts to the pole, and by utilizing stiff metal, such as angle iron, for the vertical arm C, the latter can extend above the top of the pole, and thus make the device susceptible of use with poles of minimum height.

The invention is to be understood as not limited to the details here shown, since the construction described may be modified 105 without departing from the underlying features of novelty and scope of the invention, as comprehended by the claims hereinafter.

I claim:

1. A conductor support comprising a 110 cross arm, a vertical arm attached at its upper portion to one side of a pole, and adapt-

ed to have an insulator attached thereto, the vertical arm being bifurcated at its lower end and forming diverging bracing members which are integral with the vertical 5 arm and connected to the cross arm.

2. A conductor support comprising a cross arm attached to one side of a pole, and a vertical arm adapted to be attached at its 10 upper portion to the opposite side of the pole, said vertical arm having its lower end bifurcated and forming diverging bracing members which straddle the pole and are attached to said cross arm.

3. A conductor support comprising a 15 cross arm, a vertical arm attached at one side of a pole, the vertical arm being formed of an integral piece of angle iron and split at its lower end to afford diverging bracing strips which are attached to the cross arm.

20 4. A conductor support comprising a cross arm secured to one side of a pole, a vertical arm secured to the opposite side of the pole, said vertical arm being formed of an integral piece of angle iron and split at 25 its lower end to afford diverging bracing

strips which straddle the pole and are attached to the cross arm.

5. A conductor support comprising a cross arm, a vertical arm having its lower end bifurcated to afford diverging bracing 30 members which are attached to the cross arm, said vertical arm being attached at its upper portion to one side of a pole having its upper end bent horizontally and at right angles to the cross arm to afford an insulator support.

6. A conductor support comprising a cross arm attached to one side of a pole, a vertical arm attached to the opposite side of the pole, the vertical arm being formed 40 of an integral piece of angle iron and having its lower end split to afford diverging bracing strips which are attached to the cross arm, the upper end of the vertical arm being bent horizontally and at right angles 45 to the cross arm to afford a conductor support.

In witness whereof, I have hereunto signed my name.

BENTLEY A. PLIMPTON.
